DOOR OPERATING MECHANISM

Alfred O. Williams, Battle Creek, Mich., assignor,
by mesne assignments, to Clark Equipment
Company, Buchanan, Mich., a corporation of
Michigan

Application April 20, 1936, Serial No. 75,503

9 Claims. (Cl. 268—30)

This invention relates to door operating mechanisms, and more particularly is directed to a door operating mechanism for vehicles such as busses, street cars, rail cars and the like.

5 Broadly, the present invention comprises an operating mechanism wherein as the arms carrying the door are rotated in one direction, the door itself is rotated relative to these arms in the opposite direction. The construction 10 10 closed herein provides an actuating mechanism whereby the two doors closing a door well of a vehicle such as described are simultaneously swung in opposite directions into position within the door well substantially normal to the plane 15 of the opening and at the lateral edges thereof.

15 One object of the present invention is to provide a door actuating mechanism for swinging two doors away from closed position into open position without allowing any substantial portion of the doors to pass through the space 20 forming the door well. This is of distinct advantage where the doors are employed in passenger vehicles and the space forming the door well is normally occupied by one or more passengers 25 desiring egress from the vehicle.

25 Another object of the present invention is to provide means for rotating the doors in opposite directions out of closed position by the unidirectional movement of a single actuating member, 30 and to return the doors to closed position upon reverse movement of this member. This simplifies the operation of the actuating mechanism while retaining the feature of not carrying any substantial portion of the doors through the door 35 well.

35 It has been found that with certain types of door constructions now in use, it is impossible to open the doors except by mechanical operation of the actuating mechanism. This is undesirable, since if the mechanism for any reason fails, 40 the passengers are not capable of leaving the vehicle. Further, such construction constitute a real hazard in case of fire, accident or the like, and contribute to increase the panic of the passengers in such situations. In the present construction, this condition is eliminated by providing for initial outward movement of the meeting edges of the doors, with a lost motion connection so that after predetermined movement 45 the doors can be crowded open by pressure on the inner surface thereof, this movement of the doors serving to move the actuating mechanism to door open position independently of application of the normal energizing force to the actuating mechanism. This insures that the pas-

sengers can leave the vehicle even if the operating mechanism is not in operative condition.

The present door actuating mechanism can be installed in a vehicle of the class described either for operating doors at the front or rear 5 of the vehicle, or doors placed midway between the ends thereof, since its underlying principles are the same in all cases, and only mechanical adaptation is necessary to provide for its use in any location. Primarily, it comprises an actuating member which may take the form of a longitudinally movable member connected at its ends to links which in turn are rotated by longitudinal movement of said member to effect rotation of carrier brackets which support the 10 doors. An idler gear arrangement changes the rotational direction at one end of the actuating member into rotation in the opposite direction, whereby the brackets swing inwardly of the door well in opposite directions toward the side walls 15 defining the well. The doors are pivotally mounted at substantially the median vertical plane thereof to the brackets, and suitable rack and pinion means rotatable about a fixed point 20 and actuated by rotation of said brackets serves 25 to rotate each door in a direction opposite to the direction of rotation of the bracket supporting the same as the corresponding bracket swings inwardly under the influence of the actuating member. Thus as the doors are being bodily 30 moved in a horizontal arc, they are simultaneously rotated in the opposite direction. The mechanism is so designed that the doors reach a plane parallel to the defining lateral surfaces of 35 the well as the brackets reach their full open position, insuring that minimum space within the well will be occupied by the doors in their full open position. By varying the pivotal position of the rack, the degree of rotation of the door can be correspondingly varied as desired.

40 The present construction lends itself to simplified and economical manufacture and assembly, and the operating parts are so disposed as to be immediately available for inspection, replacement and repair. Most of the parts can be made 45 of castings or standard machine parts, so that the cost of manufacturing is maintained at a minimum.

45 Other objects and advantages of the present invention will appear more fully from the following detailed description which, taken in conjunction with the accompanying drawings, will disclose to those skilled in the art the particular construction and operation of a preferred form 50 of the present invention.

In the drawings:

Figure 1 is a side elevational view, partially in section, showing one form of the present invention;

5 Figure 2 is a top plan view of the operating mechanism, the dotted lines indicating the door open position;

Figure 3 is a sectional view of the actuating cylinder;

10 Figure 4 is a top plan view, with portions broken away, of the upper door carrying bracket;

Figure 5 is a sectional view taken substantially on line 5-5 of Figure 2;

15 Figure 6 is a somewhat diagrammatic illustration of the door movement with respect to the movement of the supporting arm or bracket;

Figure 7 is a sectional view of a modified rack arm construction;

20 Figure 8 is an enlarged sectional view through a modified form of actuating cylinder;

Figure 9 is a sectional view through a preferred form of actuating cylinder; and

Figure 10 is a sectional view taken on line 10-10 of Figure 9.

25 Referring now in detail to the drawings, I have disclosed in Figure 1 a pair of doors 5 and 6, supported at their lower ends on pivoting studs 7 and 7', respectively, carried by the extending arms 8 and 8', which arms at their opposite ends are pivoted on suitable thrust bearings 9 and 9' carried within the bearing supports 10 and 10'.

At their upper ends the doors 5 and 6 are provided with offset pivot studs 12 and 12' mounted 35 in fixed position above the upper edge of the door by the supporting plates 13 and 13' which are riveted or otherwise suitably secured to the doors. It will be noted that the studs 7, 7', 12 and 12' serve to support the doors for rotation about a vertical plane extending centrally of each of the 40 door members.

As shown in Figure 2, the door well 14 comprises the space formed by a lateral defining wall 15, a vertically extending wall 16 disposed above the doors 5 and 6, and a central vertical 45 partition member 17, disposed between the respective pairs of corresponding doors 5 and 6.

In constructions of this type it is customary to provide doors either at the forward end of a 50 street car or the like, at the rear end of such vehicle, or midway between the ends. The doors usually are disposed in pairs there being two pairs at each door opening, the respective pairs being separably operable into and out of closed 55 position. Thus, in Figure 2, a second pair of doors corresponding to the doors 5 and 6 would be disposed to the right of the central partition 17, and would be operated in the same manner. One such door is diagrammatically indicated at 5A. If the door opening is at either end of the 60 vehicle due to the tapering effect produced at the ends for streamlining purposes, the outer surface of the car will extend at an angle with respect to transverse planes through the car. This angle is indicated between the partition 15, and the wall 16 forming the side wall of a 65 vehicle and framing the upper and lower edge of the door opening. Of course, if the doors are disposed midway between the ends of the vehicle, the angle between the partition 15 and the wall 16 will be a right angle.

70 Mounted on a suitable supporting surface, such as a horizontal plate disposed above the door opening and within the outer wall 16, I provide a suitable bracket 20 having means 21 receiving 75 rivets or the like for securing the same to the

supporting surface. The bracket 20 is provided with a central offset portion containing a pair of inlet ports connected to the conduits 22 and 23. These inlet ports communicate with vertical passageways 24 and 25 which, intermediate 5 their ends, open through horizontally extending passageways 26 and 27 as shown in Figure 3. The inner face portion of the offset boss is provided with a flanged surface 28 to which is secured a piston member 29 as shown by means of 10 bolts 30.

The member 29 is provided with longitudinally extending passageways 32 and 33 communicating respectively, by normally extending passageways, with the transverse passageways 26 and 27. It will thus be apparent that fluid admitted through conduit 22 to the port 24 will pass outwardly of the member 29 through the passageways 26 and 32, and similarly, fluid under pressure admitted through the conduit 23 will pass 20 outwardly of the opposite end of the member 29 through passageways 27 and 33. No communication between the conduits 22 and 23 is provided.

Each end of the member 29 is provided with a 25 cup-shaped gasket member 35, secured thereto and having a central opening aligned with the respective passageways 32 and 33. Disposed about the member 29 and reciprocatory with respect thereto, I provide the cylinder 36 having the 30 cut-away portion 37 for clearing the up-standing portion of the bracket 20. The cylinder 36 is closed at its ends by threaded cap members 38 and 39 which are provided with extending collar portions 40 and 42 preferably formed integral therewith and having vertical passageways extending therethrough.

It will be apparent that upon admission of fluid under pressure from the conduit 23 into the passageway 33, the cylinder 36 will move from the position shown in Figure 3 toward the right under the influence of the pressure built up in the right hand end of the cylinder. At the same time, fluid within the space 43 at the left hand end of the cylinder will be exhausted through the passageway 32 and the conduit 22 to allow movement of the cylinder. To effect movement in the opposite direction, the conduit 23 will be opened to exhaust and fluid under pressure will be supplied through passageway 32 to the space 43 to move the cylinder 36 to the 50 left.

It is advantageous to provide an operating mechanism in which a cushioning effect is provided as the doors approach fully open and fully 55 closed position. The present invention attains this feature by the structure shown in Figure 8.

Considering now Figure 8 in detail, it will be noted that the passage 32' in the piston 29 is enlarged in diameter, and is adapted to receive the pilot 125 of the modified cap member 38', which pilot is provided with an axial passage 126. At its outer end, the pilot is provided with an offset extension 127, which has a slight clearance as indicated at 128 with respect to the internal surface of cylinder 36.

A radial passage 129 extends from the passage 126 outward through the extension 127, and is provided with a valve seat normally engaged by the ball check valve 130. The ball 130 cannot escape from the passage by reason of the relatively small clearance at 128 with respect to the cylinder. The end of cap member 38' is provided with a radial passage 132 extending from passage 126 outwardly to the normally extending bore or passage 133 communicating with the 75

- interior of the cylinder 36. A suitable needle valve member 134, carried by the cap member 38', is adjustable toward and away from valve seat 135 in passage 132 to meter the flow of fluid therethrough. Except for these modifications, the cap member 38' corresponds to the cap member 38 of Figure 3. A similar construction is provided at the opposite end of the cylinder 36 in place of cap member 39.
- 10 In operation, upon movement of cylinder 36 to the right, as viewed in Figure 8, the fluid between the cap member and the stationary piston will be exhausted through passages 133, 132 and past valve seat 135 into passage 126. However, 15 any fluid from the interior of cylinder 36 which attempts to escape by passing through passage 129 into passage 126 will only serve to hold valve 130 on its seat, and consequently the exhaust of fluid pressure will be metered by valve 134.
- 20 As the cylinder nears the end of its movement in this direction, therefore, the fluid pressure in this end of the cylinder will restrain and cushion its movement so as to prevent the doors being forcibly slammed into their full open position.
- 25 In door closing movement, fluid under pressure is admitted to passage 32' and hence to passage 126. Under such conditions, however, the pressure unseats ball check valve 130, and this fluid can therefore escape directly into the 30 interior of the left-hand end of cylinder 36. A portion of the fluid will also pass into the cylinder through passages 132 and 133. Thus there is so substantial restriction to the entrance of fluid under pressure into the actuating end of the cylinder. However, the doors are cushioned against abrupt movement into fully closed position by the restraining action at the opposite end of the cylinder, corresponding to that previously described.
- 35 Secured in collar 40 is a stud portion 44 of a link 45, the stud portion being held in position within suitable bearing means in the collar such as a bronze bushing or the like, by means of the nut 46. The link 45 is threaded at its opposite end as indicated at 47 in Figure 2, and is received within a suitable clamp 48 having internally threaded portions receiving the link 45, and a second link 49 which corresponds to the link 45 but is provided with a downwardly extending portion 50 received within the bearing collar 52 of the arm 53. The arm 53 is mounted on a fixed pivot member 54 carried by the bracket 55 shown in Figure 5, and is keyed to a sprocket gear or pinion 56, mounted for rotation about the stud 54.
- 40 Preferably, a suitable bronze bushing 57 is interposed between the hub of the pinion 56 and the stud 54 to facilitate rotation of the pinion with respect to the stud.
- 45 This pinion or idler gear 56 is adapted to mesh with a second gear 58 keyed to the reduced portion 59 of a shaft 60 whereby longitudinal movement of the links 45 and 49 caused by movement of cylinder 36 to the right will effect rotation of arm 53 and pinion 56 in a counter-clockwise direction as viewed in Figure 2, and will thus produce clockwise rotation of shaft 60 through the gear 58 keyed thereto and driven by pinion 56.
- 50 The shaft 60 at its lower end is provided with an offset portion 62 receiving the upper end of a cylindrical member 63 that, at its lower end is welded or otherwise secured to the bracket 8. A suitable stud shaft 64 is pressed into the lower end of the member 63 and has bearing support 55 in the thrust bearings 9, the stud shaft 64 having

a roughened surface for keying it for conjoint rotation with the member 63 and shaft 60.

Considering now in detail Figure 5, it will be noted that the bracket 55 is provided with an offset portion 66 which is adapted to carry a 5 depending stud member 67 having a headed portion 68 at its lower end. The stud 67 is provided with a bronze bearing collar 69 forming a suitable bearing receiving the hub 70 of a laterally extending stud 72. A split clamp nut 73 is 10 threaded over the end of the stud 72 and also over the threaded end 74 of a rack arm 75 having the rack teeth 76 formed along one vertical surface thereof. A suitable nut 77, as shown in Figure 2, clamps the member 73 in position to 15 fix the arm 75 with respect to shaft 67, whereby the arm may rotate about this shaft as a pivot.

As shown more clearly in Figures 4 and 5, the shaft 60 is provided with a roughened portion 78 adapted to receive a bracket member 79 mounted 20 for conjoint rotation therewith. The bracket 79 is provided with a peripheral wall portion 80 forming a housing in which is disposed a roller member 82 mounted for free rotation on a stud shaft 83 carried by the bottom wall of the bracket. 25 The roller has bearing engagement with the flat surface, opposite the toothed portion of the arm 75 to maintain the teeth of this arm in engagement with the pinion 84 carried by the stud 12 forming the upper door pivot. The pinion 30 84 is keyed to the stud 12 by means of the key 85, and a suitable cap plate 86 is secured over the top of the pinion to prevent the rack 75 from moving out of engagement vertically with respect to the pinion. The stud 12 is mounted 35 for rotation relative to the bracket 79 by means of suitable bearings 87 carried in a boss portion 88 formed in the bottom wall of the bracket 79. A reinforcing rib 90 extends from the boss 88 to the hub portion of the bracket 79. Due to the 40 lateral displacement of the pivots formed by shaft 60 and the stud 67, any horizontal swinging movement of the bracket 79 will result in rotation of the pinion 84 due to meshing engagement with the teeth of the rack arm 75, which in turn will 45 rotate the stud 12 to cause corresponding rotation of the door 5. By the spacing between the pivot points, the degree of rotation of the door relative to the arcuate movement of the bracket can be determined, and this may be readily adjusted by varying the relative diameter of the 50 pinion with respect to the rack, or by the spacing of the pivots.

In the operation of the mechanism thus far described, admission of fluid under pressure to 55 the right hand end of the piston 35 will result in movement of the cylinder 36 to the right, as viewed in Figures 2 and 3, producing counter-clockwise rotation of the arm 53. This results in clockwise rotation of the pinion 58, in turn 60 producing clockwise rotation of the bracket 79. This tends to move the pinion 84 carried by the door stud 12 inwardly along the rack arm 75 resulting in the rotation of this pinion in a counter-clockwise direction to produce corresponding rotation of the door. The meeting edge 92 of the door will therefore move laterally away from the middle of the door opening and slightly outwardly, and will then rotate into final open position with the edge 92 disposed at the side of the opening and at the front edge thereof. 70

Considering now in detail Figure 6 which illustrates the movement of the door upon operation of the actuating mechanism, initial rotation of the shaft 60 results in clockwise rotation of the arm 79 moving the pivot stud 12 in an arc 75

indicated by the arrow 93. The bracket 13 which carries the door 5 is offset so that the stud 12 and the bracket 19 lie inwardly of the door when the door is in closed position as shown in full lines. As the arm 79 moves to a position where the stud 12 occupies the position shown at 12', the door moves into a position indicated at 5', with the outer edge 92 simultaneously moving slightly outwardly of the door opening and away from the center of the opening. As the arm 79 then moves to the position shown at 12'', the door moves into the position shown at 5'', the edge 92 still being disposed outwardly of the door opening and the door itself rotating in a counter-clockwise direction about the pivot point 12. When the arm 79 reaches its full open position indicated at 12''', the door is moved into a position flat against the side wall 15 of the door opening as indicated in dotted lines at 5'''.

For closing the door, the arm 79 merely reverses its pivotal movement about its pivot 60 and the door returns from its position against the wall 15 into a position closing the corresponding half of the door opening. Rotation of the shaft 60 produces corresponding rotation of the member 63 and likewise produces rotation of the arm 8 which has pivotal connection with the door 7. Thus the door is supported between the studs 7 and 12 for rotation about a central vertical plane in a direction opposite to the arcuate rotative movement of the brackets 79 and 8. It will therefore be apparent that the door at no time moves bodily into the door opening but pivots in such a manner that it at no time obstructs this passage.

The operation for opening the door 6 is substantially similar except that the countershaft 54 may be omitted since the movement of the cylinder 36 is sufficient to effect the proper direction of rotation of the shaft 60' which carries the bracket 79' supporting this door. Similar parts are indicated by corresponding primed reference numerals for the two actuating mechanisms, the arm 49' at the right hand end of the cylinder 36 being connected to an arm 95 which is mounted non-rotatively about the upper end of the shaft 60'. This causes rotation of the corresponding bracket 79' which carries the door pivots in an arc inwardly of the door opening. At the same time the rack 75 effects a counter-rotation of the door itself about a vertical plane passing centrally through the door and the door 6 therefore moves into a position against the side wall of the door opening as shown at 6' without passing through any substantial portion of the door well.

In this case, however, the brackets 79' and 8' move in a counter-clockwise direction inwardly of the door opening, while the door itself rotates in a clockwise direction about the studs 7' and 12' whereby the meeting edge 96 of the door 6 at no time passes into the door well 14 but preferably moves slightly outwardly of the door opening upon initial movement due to the location of the pivots 67' and 60' and the engagement of the rack 71' with the pinion 84. Upon movement of the cylinder 36 to the left for door closing movement, the arm 95 is rotated in a clockwise direction to produce corresponding rotation of the brackets 79' and 8' which carry the door outwardly, while the door at the same time rotates in a counter-clockwise direction into a common plane with the door 5 which is moving outwardly from the opposite side of the door well. The bracket 55', which corresponds somewhat to the bracket

55 at the left hand side of the Figure 2 is extended to provide for supporting the shaft 100 which corresponds to the shaft 60 associated with the door 5 and which carries a pinion 102 corresponding to the pinion 58. A duplication of the operating mechanism thus far described is provided to the right of the bracket 55' for the purpose of actuating a similar pair of doors at the opposite sides of the partition 17. The cylinder 36 and the corresponding cylinder which controls the door 5-A and its companion door (not shown) may be operated simultaneously or independently as desired, preferably being operated independently so that either pair of doors may be opened at will.

It is distinctly advisable to have the meeting edges 92 and 96 of the doors 5 and 6 move slightly outwardly upon initial door opening movement in order that passengers standing in the doorway will not interfere in the operation of the doors nor be injured by the doors moving inwardly, and also to provide for outward movement caused by pressure internally of the doors to start the door mechanism in operation independently of the cylinder 36. When this cylinder or the control means becomes inoperative, a slight outward pressure on the meeting edges of the doors, with no pressure in either end of the cylinder 36, will cause the doors to be manually opened since this outward pressure will cause rotation of the racks which will in turn swing the brackets in counter directions to carry the doors into open position.

It should be noted that the brackets 79 and 79' are designed for right and left hand mounting and the side walls 80 and 80' are provided with cutaway portions 103 and 103' which provide for entrance of the rack arm thereinto, and also allow the brackets to swing into position about the pivots 67 and 67'. The brackets are each provided with cover plates 104 and 104' which may be secured thereto in any suitable manner. These cover plates are provided with arcuate slots 105 as shown in Figure 4 to receive the depending boss portion of the extensions 66 and 66' of the brackets 55 and 55' and the hubs 70 and 70' of the arms 72 and 72'.

In an alternative form of the present invention, I have provided for a lost motion connection between the rack arm and its associated pivot whereby, if an obstruction is preventing initial movement of the door, the operating mechanism can begin its rotation while the rack remains stationary, and after slight movement of the operating mechanism, the door will then snap away from the obstruction and rotate into its fully open or fully closed position without damaging the actuating mechanism.

Thus in Figure 7 I provide the pivot stud 110 carried by a supporting bracket 112 which serves as a pivot for the arm 113 having the hub portion 114 pivotally engaged about the bearing bushing 115 carried by the stud. Adjacent its outer end, the arm 113 is provided with a pin 116 which engages in suitable slots 117 formed in a tubular extension 118 of the rack 75. The inner end of the tubular extension 118 is provided with the flanged collar 119 against which one end of the spring 120 engages. The spring 120 encircles the extension 118 and at its opposite end bears against a supporting ring 122 which is held against axial movement by engagement with the pin 116. Thus it will be seen that the arm 75 has limited axial or telescoping movement with respect to the arm 113, and this move-

ment results in compression of the spring 120 whereby the spring is biased to return the arms to their normal position shown in Figure 7. Thus if for some reason an obstruction is placed between the meeting edges of the doors preventing them from closing fully, the operating mechanism can move to fully closed position which will result in compression of the spring 120 and upon removal of the obstruction, the springs will move the doors to their fully closed position. This is desirable to prevent accidents and is also effective to provide for opening the doors slightly when the operating mechanism is rendered inoperative, whereby they can be grasped and moved to their fully opened position. Such a connection can be applied to each of the rack arms.

The amount of rotation of the brackets 79 and 79' is determined by the actuating mechanism 36 and the ratio of the gears 56 and 58. The amount of rotation of the brackets 79 and 79' is determined by the actuating mechanism 36 and the ratio of the gears 56 and 58. The amount of rotation of the door with respect to the arms 79 and 79' is determined by the diameter and gear tooth ratio of the rack and pinion mechanism and by the spacing of the pivot points 68 and 67, and the corresponding pivots 60' and 67'. Thus the doors can be moved to a position at right angles with respect to their closed position while the arm 79 moves through only a portion of the arc, or if the side wall of the car is angled with respect to the door opening, the doors can be made to move either a greater or lesser distance upon corresponding movement of the carrying arms. In one embodiment of the invention the doors move through an angle of 165° with respect to the arms carrying the same, while these arms move through an arc of from 75 to 90°. It will thus be apparent that the rate of angular movement of the doors can be made to vary with respect to the rate of movement of the arms in any desired manner.

In Figures 9 and 10 I have disclosed a preferred embodiment of a construction for cushioning the movement of the doors into and out of closed and opened position. The supporting bracket 20' corresponding to the bracket 20 of Figure 2 is provided with the two ports 140 and 142 which terminate in laterally extending openings 143 and 144, respectively, communicating with the ports 145 and 146 of the stationary piston 147 which is bolted to the face 148 of the bracket 20' by means of a plurality of bolts 149.

The piston 147 is of a form similar to that shown in Figure 3 but is provided with enlarged axially extending passageways 150 and 152 directed toward opposite ends of the piston and provided adjacent the opposite ends with enlarged portions 153. Each end of the piston 147 is provided with a radially extending flange portion 154 which is of a diameter slightly less than the diameter of the interior of the cylinder 155. The cylinder 155 is provided at each end with a threaded cap member 156 closing the end and having an axially projecting stem portion 157 which is centered for reciprocal movement in the passageways 150 and 152. The stem 157 is axially bored to provide the passageway 158 which terminates in a radially extending passageway 159, as shown in detail in Figure 10, having a valve seat 160 controlled by the metering valve member 162 threaded radially into the cap member 156. The flow of fluid from the passageway 158 through the passageway 159 and past the

valve seat 160 is controlled by the valve 162 which meters the escape of fluid through the opening 163 into the interior of the cylinder 155. Each of the cap members 156 is provided with an extending arm portion 166 corresponding to the arms 40 and 42 of the members 38 and 39 of Figure 3.

Secured to the outer face of the piston flanges 154 is a leather cup gasket 167 adapted to have sealing engagement with the internal surface of the cylinder 155 and held into position by a plurality of screws 168 which also serve to position a plate-like spider member 169 in position.

Slidably mounted on the external surface of the stem 157 is a sleeve valve member 170 having a radially extending flange 172 which is locked between the inner end of the spider member 169 and the face of the piston. A suitable resilient gasket member 173 seated in an annular recess formed at the outer end of the enlarged portion 153 of the passageway 150 limits the reciprocal movement of the slide 170 with respect to the end of the piston. The spider member 169 is provided with a plurality of circumferentially spaced openings 174 which provide communication between the interior of the cylinder 155 between the piston and the cap 156 and the passageway 150.

In the operation of the structure shown in Figures 9 and 10 when fluid under pressure is admitted through the passageway 150 and port 145 into the passage 150, this fluid escapes through the enlarged passage 153 and the ports 174 into the interior of the cylinder between the cap member and the piston. A portion of the fluid also passes through the stem 157 and past the needle valve 162 into the interior of the cylinder. The increase of pressure in the interior of the cylinder forces the cylinder 155 to the left as viewed in Figure 9, and results in movement of the stem 157 axially outwardly of the passage 150. This results in the sleeve member closing off the port 175, forming communication between the passageway 158 and the enlarged portion 153 of the passageway 150. This passage of fluid into the interior of the cylinder 155 between the gasket 167 and the cap 156 moves the cylinder into a position to open the doors to their full open position.

In closing the doors, the passageway 142 is supplied with fluid under pressure which produces a corresponding flow of fluid through the passageway 152 at the opposite end of the piston and tends to move the cylinder 155 to the right. This results in inward movement of the stem 157 within the passageway 150 and produces an increase in pressure of the fluid confined in the gasket 167 and the cap member 156 within the left hand end of the cylinder. The sleeve member 170 moves into position against the gasket 173 and due to the tapered surface 176, a sealing engagement between the flange 172 and the gasket 173 is provided. This prevents escape of fluid from the ports 174 past the flange 172 and the enlarged portion 153 and into the passage 150. As a result the fluid confined between the end of the cylinder and the piston must escape through the port 163 and past the needle valve 162 and into the passage 158. Since this path of flow is metered, it will be obvious that the fluid can escape only at a given rate and consequently, the cylinder will be cushioned against abrupt closing movement by reason of the body of fluid confined in the end at which it escapes at a slow rate into the passage 150 into the stem 157.

By adjusting the position of the valve 162, any desired cushioning effect can be provided in accordance with the rate of closing which is to be effected.

- 5 It is obvious that during door opening movement the same type of cushioning action is produced at the right hand end of the cylinder 155 and consequently, the doors cannot be moved abruptly into their full open position, but are 10 cushioned so as to at first move at a relatively fast rate in their opening movement and then slow down to any given movement as they near their full open position.

It is also to be pointed out that since the sleeve 15 member 170 closes the port 175 after a predetermined movement of the cylinder in door opening position, the full fluid pressure is not transmitted as rapidly to the head of the piston after the cylinder has reached a position such that the member 170 covers the port 175 and thus, the effective force tending to open the doors is reduced as the doors near their full open position. A similar action occurs at the opposite end of the cylinder during door closing movement.

- 25 It is therefore apparent that I have provided an effective mechanism for cushioning the doors as they move into fully opened and fully closed positions whereby their operation is accomplished with the least amount of strain on the mechanism, while yet maintaining an efficient rate of movement during the major portion of each operation.

I am aware that various changes in construction and details of operation can be made in the 35 present invention without departing from the underlying features thereof, and I therefore do not intend to be limited, except as defined by the scope and spirit of the appended claims.

I claim:

- 40 1. In a door operating mechanism, a vertical shaft having a gear at one end thereof and having a pair of vertically spaced horizontal brackets provided at their extending ends with pivot supporting means, a door having pivots at the top 45 and bottom thereof intermediate its lateral edges supported in said brackets, one of said brackets forming a housing about the adjacent door pivot, a pinion on one of said door pivots within said housing, means pivoted independently 50 of said shaft extending into said housing and engaging said pinion, means on the corresponding bracket holding said means in engagement with said pinion, and means engaging the gear on said shaft for rotating said shaft to swing the door bodily about the shaft as a center, said pinion 55 engaging means rotating the door about its pivot in a direction opposite to the direction of rotation of said shaft.

2. A door mechanism comprising a door pivoted intermediate its lateral edges, a supporting lever for the door pivoted outwardly of one edge of said door and forming a housing for the door pivot, means for rotating said lever through a predetermined arc, and means extending into 65 said housing and engaging the door pivot and having an external pivot laterally offset from the pivot of said lever for producing a rotational movement of said door with respect to said lever through an arc at least twice the arc through 70 which said lever rotates.

3. A bracket for a door operating mechanism of the class described comprising a substantially planar body member having a boss portion at one end thereof adapted to receive a supporting shaft, the body member being provided with a

peripheral flange forming a cup-shaped recess, a thrust bearing portion in said recess adjacent the other end of said body member adapted to receive a pivot stud of a door, a cover for said bracket engaging the upper edge of said flange and enclosing said pivot stud, said flange having an opening in the lateral surface thereof adapted to receive means extending thereinto for rotating said stud.

4. A bracket for a door operating mechanism of the class described comprising a substantially planar body member having a boss portion at one end thereof adapted to receive a supporting shaft, the body member being provided with a peripheral flange forming a cup-shaped recess, a thrust bearing portion in said recess adjacent the other end of said body member adapted to receive a pivot stud of a door, a roller carried by said bracket adjacent said bearing portion and a cover for said bracket engaging the upper edge of said flange and enclosing said pivot stud and roller, said flange having an opening in the lateral surface thereof adapted to receive a rack engageable with a gear on said stud and held in position by said roller.

5. A door operating mechanism comprising a door, a door operating shaft, a pair of levers mounted on the shaft for supporting said door, one of said levers forming a housing, and means for causing the door to swing and pivot as it opens and closes, a substantial portion of said means being mounted within the housing formed by one of said levers.

6. In a door operating mechanism the combination comprising a rotatably supported door shaft, a pair of levers secured to said shaft, a door pivotally mounted on said levers, and means pivotally interconnecting the door with a point fixed with respect to the door to cause it to rotate on the levers as it swings with them, said 40 means including a pair of relatively movable members and a spring for resisting their relative movement.

7. In a door operating mechanism the combination comprising a rotatably supported door shaft, a motive device for rotating said shaft, a pair of levers secured to said shaft for rotation therewith, a door, means for pivotally mounting the door between said levers including a pivot pin connected to the door, means interconnecting the pivot pin with a point fixed with respect to the door to cause it to rotate as it swings, said means including a pair of relatively movable members and a spring for resisting relative movement thereof.

8. A door operating mechanism as described comprising a door shaft, a door rotatably supported on a pair of arms secured to said shaft, one of said arms being in the form of a casing, means for rotating said shaft, and means including a gear train interconnecting the door with the shaft to cause it to rotate on its axis of support on the levers as it swings with the door shaft, said gear train being within said casing.

9. A door operating mechanism comprising a power operated rotatable shaft, a pair of spaced levers connected to the shaft, a door pivotally mounted between the levers, and mechanism connected to the door for effecting combined swinging and rotative movement as the door opens including a resilient connection whereby the door may be manually opened while said mechanism is in door closed position.
